Incorporated, Cedar Rapids, Iowa, a corpora-
tion of Delaware

Application August 2, 1934, Serial No. 738,092

8 Claims. (Cl. 37—144)

Our invention relates to earth moving devices and has particular relation to a scraper blade, a plow or the like, and means for adjustably securing it to a tractor or other prime mover.

It is a common expedient to mount a scraper blade, a plow, or the like on a framework which is pivotally attached to a tractor, with the blade in front of the tractor, but we have observed that such mountings are not always satisfactory for the reason that the blade is not readily adjustable to vary the depth and angle of cut and to throw the material to one side or the other as desired. The devices of the prior art have been found at times unable to hold the degree, angle and depth cut under load. In most of the devices of the prior art two men were required to change adjustment of the blade.

We have, therefore, devised a new and improved mounting for scraper blades and the like, which permits adjustment of the blade to push material ahead of it, or to throw material to the right or the left as desired, and which permits tilting of the blade from side to side. The construction of the blade-attaching means is simple and sturdy, and the position of the blade will not vary under load.

A general object of our invention is to provide a new and improved means for attaching a scraper blade, a plow or the like to a framework, which in turn is adapted to be pivotally attached to a tractor or other prime mover.

A more particular object of our invention is to provide an attaching means for attaching a scraper blade or the like to a tractor to permit adjustment of the blade, to permit tilting thereof, and to permit the blade to be swung about a vertical axis to throw material to the right or left as desired.

Another object of our invention is to provide an attaching means of the above description which is simple and rugged in construction and reliable and sturdy in operation.

Another object of our invention is to provide simple and sturdy means for locking the blade in any desired position of tilt.

Another object of our invention is to provide a very simple and sturdy universal joint means for attaching the plow blade to the plow blade supporting structure.

Another object of our invention is to provide means for meeting the forces acting upon the blade which tend to rotate it about its own horizontal longitudinal axis.

Another object of our invention is to provide an end plate for the plow blade which is so con-

structed that when one part wears, the plate may be reversed to present a new surface to the ground.

Another object of our invention is to provide means for substantially doubling the life of the parts of the blade which are subjected to the greatest wear.

Another object of our invention is to provide a device of the above character which will connect the blade to the blade-supporting frame at both ends and at the center and in which all of these connections will take both push and pull.

Another object of our invention is to provide a device of the above character which may be adjusted by one man under all of the operating conditions which may be encountered.

Other and further objects and features of our invention will be more apparent to those skilled in the art upon a consideration of the accompanying drawing and following specification, wherein is disclosed a single embodiment of the invention, with the understanding, however, that such changes may be made therein as fall within the scope of the appended claims without departing from the spirit of the invention.

In said drawing:

Figure 1 is a plan view of the front end of a plow blade supporting structure with a plow blade attached thereto in accordance with one embodiment of our invention.

Figure 2 is an elevational view of the front portion of a plow supporting framework showing the means utilized, in accordance with one embodiment of our invention, for locking the blade to the blade-supporting framework when the blade is in the "bulldozing" position.

Figure 3 is a view, partly in elevation and partly in section, taken from behind the blade showing the blade attached to the blade-supporting framework in a tilted "trailbuilding" position of the blade, as illustrated in Figure 1.

Figure 4 is a side elevational view, partly in perspective and partly in section, of the means for pivotally attaching a plow blade to a blade-supporting framework, illustrated in Figures 1 and 3 portions of the device having been broken away to show the details of construction of the hidden parts.

Figure 5 is a view in perspective of the end of a blade showing particularly a blade end member which has been constructed according to an embodiment of our invention.

This invention is concerned with a device such as shown in the patent to Herbert H. Pearson, No.

1,961,011 on earth moving devices and also in the patent to R. E. Choate et al., No. 2,011,191.

Referring now to the drawing, there is indicated at 10, the front end of a tractor, with the nose portion of a scraper blade supporting framework indicated generally at 11. Since the tractor and the scraper blade supporting framework constitute no part of our present invention except in this connection with the scraper blade and the attaching means therefor, they will not be described in detail, except insofar as they constitute a part of the structure for adjustably securing the blade.

The scraper blade supporting framework 11 includes beams 12 and 13 extending one on each side of the tractor toward the rear thereof and usually pivotally engaged to the tractor at some intermediate point along the sides thereof to permit the front end of the supporting framework to be raised and lowered as desired to raise and lower the scraper blade. In the present case the front end or "nose" of the supporting framework is comprised of a pair of forwardly and inwardly inclined and extending beams 16 and 17 attached to the members 12 and 13 by means of plates 18 and 19 and joined at their inner ends by a short, transversely-extending channel or nose 21.

In this embodiment of the invention, a cap bracket 81 is secured to the upper rear face and a pad bracket 83 to the lower rear face of the plow blade 28, in any suitable manner as by welding or bolting them to the blade.

A T-shaped member 71 has its "cross bar" portion 77 pivotally engaged to the cap bracket and to the pad bracket 83 by means of a bottom cap bracket 82, and the scraper or plow blade 28 may pivot from side to side in a horizontal plane on the vertically-extending cylindrical "cross bar" 77 of the T-shaped member 71. The stem of the T-shaped member, indicated at 72, projects through the nose 21 and is held in place by a bolt 73, washer 74 and nut 76. The bolt 73 projects entirely through the stem 72 of the T-shaped member and the nose 21. The blade thus may also pivot about in a vertical plane with the bolt 73 as a horizontal axis. The structure of this center pivot mounting is more particularly hereinafter described.

It is desirable that the blade be adjustable to at least three positions in the horizontal plane, that is, two extreme positions, termed the "trailbuilding" positions, in which the blade will throw material to the right or to the left, and an intermediate or "bulldozing" position in which the blade is at right angles to the longitudinal axis of the earth moving device, in which position it is adapted to push material ahead of it, as in levelling off an irregular ground surface.

It is desirable furthermore that the blade, in the "trailbuilding" positions, be adjustable in vertical planes about the longitudinal axis of the earth moving device so that the blade will cut equally on both sides, or will make an angular cut which is deeper on one side than the other, as in "crowning" a road or the like. It is desirable, in all positions, that the blade be firmly held so that the depth and angle of cut will not vary under load except if and when changed by the operator.

In order to accomplish the results above noted we have provided a structure so constructed that the blade is amply braced and supported at both ends thereof as well as at the middle. The frame members 12 and 13 are box sections open at their front ends and the brackets or connecting plates

18 and 19 surround these box-like members, and are so arranged that the front end of the box members 12 and 13 are left open. A pair of channel members 36 and 37 are adapted to fit within the box frame members 12 and 13. These channel members are of sufficient length that, when in the extended position as shown in Figure 1, the channels still have sufficient bearings within the box frame members that the channels are rigidly supported to prevent movement up and down of the outer ends of the channels. The channels 36 and 37 may be locked in any one of three desired positions by means of pins 38 which are passed through aligned openings 39 in the channels and openings 41 in the box frame members.

A pair of swivel clevis members or brackets 42 and 43 are provided on the front ends of the channels 36 and 37. The brackets 42 and 43 are provided with forwardly-extending clevis ears 44 and 46 which are somewhat similar to the clevis ears 81 and 82 at the center of the blade. Clevis eyes 47 and 48 are adapted to be engaged within the clevis ears 44 and 46 by means of pins 51 and 52 and the front portions of these eyes are each provided with double lobed ears 53 and 54 in order that each of the eye brackets 47 and 48 may be engaged at two points to two pairs of curved flanges 56 and 57, which are fastened to the rear face of the scraper blade 28.

The ears 53 and 54 are adapted to be secured in selected positions with respect to the curved flanges 56 and 57, by means of pins 61 and 62 which pass through openings 63 and 64 in the respective flanges 56a, 56b, 57a, and 57b. A series of openings 63 and 64 are provided in the respective flanges 56 and 57 and openings 66 are provided in the ears 53 and 54. It is apparent that the blade may be tilted from side to side as desired and will be held in any desired position of tilt by engaging the pins 61 and 62 in suitable openings of flanges 56 and 57.

The eye brackets 47 and 48 may swivel from side to side on the pins 51 and 52 and the channels 36 and 37 may be slid in and out with regard to the box members 12 and 13 so as to hold the blade in either of the two trailbuilding positions. When the desired trailbuilding position has been reached the channels 36 and 37 are locked in the box members 12 and 13 by means of pins 38. The swivel eyes 47 and 48 must be disengaged from flanges 56 and 57 while changing from one "trailbuilding" position to the other. By providing swivels at these points the same structure may be utilized for securing the blade to the blade-supporting framework in both "trailbuilding" positions, since the swivels swing from side to side.

In the intermediate or "bulldozing" position of the blade the swivels 47 and 48 are attached to an inner set of short flanges 50 and 55, similar to the flanges 56 and 57, by means of the pins 61 and 62. The dotted lines B and T₂ in Figure 1 indicate the position the front edge of the blade occupies in the "bulldozing" and alternate "trailbuilding" positions, respectively.

In Figure 4 we have shown in detail the center pivot mounting shown in Figures 1 and 3, for mounting the scraper blade on the nose of the blade-supporting framework. In this embodiment of our invention a large T-shaped casting 71 is employed for pivotally engaging the blade to the frame. This T-shaped member, which we may term the "blade pivot", has a shaft portion 72 which is adapted to project through a suitable opening in the channel or nose 21 and 75

to be rotatably mounted within this channel. A sleeve 70 is engaged within the nose 21 and over the shaft portion 72. This shaft portion is adapted to be held in place by a through bolt 73 having a washer 74 and lock nut 76 adapted to bear against the rear face of the nose 21. An enlarged disc-like portion 75 of the upright or cross bar of the member 71 is so positioned as to bear against the front face of the nose 21 in order 10 to provide a large bearing surface to meet the force imparted to the blade by pushing the material in front of the blade.

The front portion of the blade pivot, constituting the cross bar of the T-shaped member, is a vertically-extending, substantially cylindrical member 77 having reduced stub shaft portions 77a and 77b at top and bottom to afford means for pivotally attaching the blade to the T-shaped member 71.

20 A cap 78, which may be termed "the upper blade pivot cap", is adapted to fit over the stub shaft 77a at the upper end of the cylindrical member 77 and a like member which may be termed "the bottom blade pivot cap" 79 is adapted to fit over the stub shaft 77b at the lower end of the cylindrical member 77. The cap member 78 is provided with a forwardly-extending bracket 81 which is preferably welded to the rear face of the central upper portion of the 30 scraper blade 28. The bottom pivot cap 79 is provided with another forwardly-extending bracket 82 which is adapted to be removably engaged to a suitable pad 83 on the rear, central, lower face of the blade. The bracket 82 is preferably removably engaged to the blade 28 by means 35 of the bolts 84. In assembling the blade on the blade pivot 71 the blade is placed in front of the pivot with the cap 78 on the stub shaft 77a. The bracket 82 is then placed on the stub shaft 77b 40 and fastened by means of the bolts 84 to the blade. Assembly and disassembly of the blade on the blade support is therefore quite readily accomplished.

It is apparent that the blade 28 will pivot 45 about a horizontally-extending axis represented by the bolt 73 and may pivot about a vertically-extending axis as represented by the cross bar 77 of the pivot 71. This pivot is strong and sturdy and is readily assembled and disassembled. 50 The entire assembly may be removed by removing the nut 76 from bolt 73.

A scraper blade, such as the scraper blade 28, is subject to greatest wear at the bottom or cutting edge 91 and at the base of the blade ends at 55 the point 93. If wear at these portions of the blade is met the blade will last indefinitely. In other words, the life of the blade depends to a great extent upon the life of these parts. In order to prolong the life of a blade we preferably 60 provide a separate cutting edge 94 of a very hard material for the blade. This cutting edge is secured to the blade as by means of bolts 96 and may thus be readily replaced if it becomes worn.

We have devised novel removable blade ends 65 95 for meeting wear at the ends of the blade. These blade ends have flattened bottom and top surfaces as indicated at 97 and 98, respectively, and the angles which the surfaces 97 and 98 make with the curved front faces 99 of the blade ends 70 are identical. These angles are such that the lower faces of the blade ends are substantially parallel to the ground. The blade ends are held in place on the blades by means of bolts 101 and the side faces 102 slope inwardly so that 75 when the blade is in the trailbuilding position

the side 102 of the forward blade end is parallel to the longitudinal axis of the earth moving device. If the lower faces of the blade ends become worn both blade ends may be removed and their positions reversed, that is, the blade ends may be placed on opposite ends of the blade 28 and in this manner new faces will be presented to the ground where the greatest wear is encountered. In this way the useful life of the blade ends is doubled.

It is apparent that modifications may be made by those skilled in the art and such modifications may be made without departing from the spirit and scope of my invention as set forth in the appended claims.

We claim:

1. A means of mounting a plow blade on a plow blade-supporting framework including a center pivot mounting comprising a T-shaped member having the stem portion of the T-shaped member pivotally engaged in the plow supporting framework for a pivotal movement about a horizontal axis, and cap members at either end of the cross bar portion of the T-shaped member pivotally engaged thereto and secured 20 to the plow blade to permit pivotal movement about a vertical axis.

2. An earth moving device including a plow blade and a plow blade supporting device and means for adjustably securing the plow blade to a plow blade supporting framework comprising a central pivot connection between the blade and framework, opposed arcuate flange members at either end of the blade, push poles adapted to be slidingly engaged within the side members of the frame, means on the outer end of the push poles for connection with the arcuate flanges, and means for engaging the push poles within the framework for holding them at predetermined positions.

3. An earth moving device including a plow blade and a plow blade supporting framework and means for locking the ends of the plow blade to the plow blade supporting framework including a center pivot mounting, arcuate flange 45 members on the ends of the plow blade, push poles in the side frame members adapted for longitudinal movement therein, brackets on the rear face of the plow blade adjacent the arcuate members, and swivel means on the ends of 50 the push poles for engaging either the arcuate members or the bracket members.

4. In an earth moving device, a plow blade and a plow blade supporting structure, a push pole slidably engaged to the plow blade supporting structure and having a swivel end pivotally engaged to the push pole for rotation about a pivotal axis and a pair of curved flanges on the rear face of the end of the plow blade adapted to receive the free portion of the swivel and 60 means for pivotally engaging the plow blade with the supporting structure near the center of the blade whereby the blade may be tilted from side to side as for crowning a road and may also be positioned with one end or the other to 65 the rear to discharge material to one side or the other.

5. A pivot mounting for mounting a blade on a blade supporting framework comprising flange and cap members adapted to be secured to the 70 blade and a T-shaped member with the cross bar of the T-shaped member adapted to be rotatably received in the aforementioned cap members and having the stem portion pivotally engaged within the blade supporting framework.

6. A pivot mounting for mounting a blade on a blade supporting framework comprising brackets mounted top and bottom on the rear of the blade and having vertically extending openings therein, a T-shaped member having the cross bar of the T received in the openings in the brackets and having the stem portion projecting into the nose of the blade supporting framework and rotatably mounted therein and retaining means on the stem for retaining it in the blade supporting framework.

7. An earth moving device including a plow blade, a plow blade supporting framework, and means for locking the ends of the plow blade to the plow blade supporting framework including a center pivot mounting, flange members on the ends of the plow blade, push poles having a sliding adjustable connection with the side frame members, swivel members pivotally engaged to the front ends of each push pole, means for pinning the swivels to the flange members on the ends of the plow blade in a plurality of positions to permit tilting of the blade about its transverse axis, and means for pinning the push

poles to the side frame members in a plurality of positions to permit adjustment of the blade about its vertical axis.

8. An earth moving device including a plow blade, a plow blade supporting framework and means for engaging the plow blade to the plow blade supporting framework including a pivotal connection between the central portion of the blade and the front part of the blade supporting framework, flanges on the rear face of the blade adjacent the ends thereof, push pole members having cooperative relation with the side members of the blade supporting framework whereby one set of members is received at least partially in the other set, means for pinning the push poles to the side members in a plurality of positions, swivels pivotally engaged on the front ends of the push poles and means for pinning the swivels to the flanges on the rear of the blade in a plurality of positions to permit tilting of the blade about its transverse axis.

WENDELL D. BARRETT.
